UNITED STATES PATENT OFFICE.

WILLIAM P. HAMMOND, OF PASSAIC, NEW JERSEY, ASSIGNOR TO THE MOTOMETER COMPANY, OF NEW YORK, N. Y., A CORPORATION OF NEW YORK.

TEMPERATURE-INDICATING DEVICE FOR WATER-COOLING SYSTEMS FOR INTERNAL-COMBUSTION ENGINES.

15,063.

Specification of Reissued Letters Patent. Reissued Mar. 15, 1921.

Original No. 1,178,154, dated April 4, 1916, Serial No. 20,984, filed April 13, 1915. Application for re-issue filed June 14, 1916. Serial No. 103,699.

To all whom it may concern:

Be it known that I, WILLIAM P. HAMMOND, a citizen of the United States, residing in Passaic, county of Passaic, and State 5 of New Jersey, have invented certain new and useful Improvements in Temperature-Indicating Devices for Water-Cooling Systems for Internal-Combustion Engines, of which the following, taken in connection 10 with the accompanying sheet of drawings, is a full, clear, and concise description.

My present invention relates to that general type of device disclosed in United States Letters Patent, No. 1,090,776, granted 15 to one Harrison H. Boyce, and has for its objects to provide means whereby the temperature indicating element will at all times indicate the actual temperature of the cooling medium in the circulating system of an internal combustion engine. The device of 20 the patent mentioned comprises a temperature indicating element supported by the filler cap of an automobile radiator and depending into the air space above the water 25 level therein, and, as a consequence thereof, the responsive element is influenced directly by the temperature of said air space, which, under normal running conditions, is considerably below the actual temperature of the 30 cooling medium, sometimes as much as 20 to 30 degrees. At the point of vaporization, however, where the circulating water is converted into steam, by abnormal running conditions, the temperature responsive element 35 is caused to rise suddenly an appreciable distance along the scale of the instrument, this jump indicating to the driver in an impressive manner, the existence of an abnormal condition—a useful and highly meritorious 40 feature in itself. The actual temperature condition of the cooling water, however, is never indicated under normal running conditions, and it is the object of my present invention to make an instrument of this general type so operate that one may be enabled 45 at all times to know the actual temperature of the water as it circulates through the system, and to do this preferably without changing the form of the Boyce device.

It is impossible to construct a heat responsive device capable of being mounted upon the radiator cap and being removable there-

with, to project into or be partly submerged in the water because the quantity of the latter is constantly varying. The cooling 55 water diminishes as the running of the engine continues and frequently falls below the top of the bank of air tubes, where no instrument would under any circumstances come in contact with it. For the accomplishment 60 of the object of this invention, I provide an extension to the return pipe of the radiator through which I bring the cooling medium constantly and at all times during 65 its circulation in contact with the heat responsive element irrespective of the varying quantity of the water in the radiator.

Thus it will be seen that what I accomplish is the maintaining of an artificial 70 water level within the radiator which, notwithstanding any fall in the level of the water in the radiator or cooling system, is constant or so nearly so as to permit the temperature responsive element to at all times coöperate therewith, and which is constantly fed by the hot water returning from 75 the engine so that its temperature is always representative of the thermal condition of the engine.

Through the instrumentality of my device, an accurate indication of the temperature 80 of the cooling medium is obtained, whether it be for experimental purposes or as a constant signal to the automobile driver.

In the accompanying drawings, Figure 1 85 indicates a vertical cross-sectional view of a fragmentary part of a radiator, a detachable filler cap removably supporting the heat indicator, and the return pipe of the circulating system partly in full, supporting the 90 extension tube by which the artificial water level is maintained. Fig. 2 is a like view on an enlarged scale showing a part of the bank 95 of radiator air tubes and the flexible connection between the return pipes of the engine and the radiator. Fig. 3 is a modification showing the manner in which the present invention may be used in connection with heating indicating devices, which are provided with short stems, which, in some instances, may not project below the bottom 100 of the filler opening. Fig. 4 is a further modification illustrating the manner in which a flexible tube may be used for the

purpose of conveying the entire volume of circulating fluid issuing from the return pipe so as to bring it into contact with the temperature-responsive element of the indicating device.

The radiator 1, is generally provided with a cylindrical extension 2, which serves as an opening through which the supply of the cooling water in the circulating system is replenished. This cylindrical extension is closed by a cap 3, which is removably connected thereto by the usual screw threads. The cap 3 carries the indicating device 4 which, in the present instance, is illustrated as comprising a temperature responsive element 5 and a scale 6. A lower projecting sleeve or sheath 7 envelops the lower part of the heat responsive element and protects the same from breakage. A series of apertures 8 are provided in the extremity of this sheath, and as the heat responsive element is supported and insulated from the frame of the device and the sheath, it is obvious that the water may be brought into actual contact with the heat responsive element, so that the latter will be operated thereby.

The numeral 9 indicates the bank of air tubes which form a structural part of the radiator, 10 the return pipe which generally forms a part of the radiator, and 11^a a flexible connection between the end of the return pipe of the water jackets of engine cylinders and the return pipe of the radiator.

It will be understood that as thus far described the construction is well-known and forms no part of my present invention other than as the same may be used in a co-operative way to accomplish the purpose of my invention.

It will also be understood from what has heretofore been said that the quantity and rate of flow of the circulating fluid varies under variable conditions. For instance, if one should operate an engine for a given length of time without a replenishment of the circulating fluid, the water-line within the radiator will fall to such an extent that any device projecting into the mouth of the filler opening, would not, under any circumstances, contact therewith. Where the capacity of the radiator is large, the engine may safely run with much less water than the designed capacity of the radiator, particularly so, in extremely cold weather. In order, therefore, to insure the temperature responsive element constantly contacting with the circulating medium irrespective of its quantity, or rate of flow, I extend the return pipe to the radiator inwardly to a point beneath the temperature responsive device when the latter is in normal operative position, so that the water will be caused to flow in contact with the device. I do this, preferably, by using a supplemental pipe 11, 60 which has a close sliding fit within the

return pipe 10. This pipe 11 is slipped through the return pipe 10, the flexible connection 11^a being removed for the purpose.

The pipe 11 is closed at its inner end as at 12 and a portion of the side of the pipe is cut away to provide the aperture 13 through which the end of the instrument or heat responsive indicating element is inserted. This aperture 13 serves as an outlet for the return water coming from the water jackets of the engine, and inasmuch as the end of the heat responsive indicating element projects well within the pipe 11, the water is caused to circulate therewith in its passage to the radiator through the aperture 13. A correct reading of the actual temperature of the water is thus obtained by reason of the operation of the expansion of the heat responsive medium in conjunction with the scale of the dial 6. In the present instance, the temperature responsive indicating element is made long enough to project well below the top of the radiator, preferably to a point nearly in line with the lower wall of the return pipe.

In cases where the temperature responsive element does not extend below the cylindrical part of the radiator opening, it is desirable to provide an upwardly extending pipe 14, which will be concentrically positioned with respect to the cylindrical filler opening and the heat responsive element, the latter projecting downwardly and centrally thereinto, as shown in Fig. 3. The pipe 14 may be suitably secured to the pipe 11, by a union, or any equivalent means, so that the return from the water jackets of the engine will be caused to flow upwardly through the pipe 14 and over the edge 15, in to the radiator, and in its passage, contact with the temperature responsive element 5, so as to cause the latter to respond and indicate the temperature condition of the water on the dial 6. In both of these described instances the cooling medium is caused to contact with the heat responsive element and operate the latter in the well known manner, and, by so doing, knowledge may be obtained of the actual thermal condition of the system, and any abnormality of such condition may at once be detected.

By the use of my improvement, a convenient and ready understanding of the existing engine conditions can be had, and a useful application of the device to experimental purposes in connection with the manufacture of internal combustion engines obtained.

While I have illustrated and described but one specific form or construction in which my invention may find embodiment, I do not wish to be limited specifically thereto, as other means may be provided whereby the return water to the radiator may be caused to flow into contact with the

heat responsive element. For instance, it may be feasible to employ a flexible pipe or tube as shown at 16 in Fig. 4, which may be carried by the tube 7, which, when inserted 5 in place within the radiator, will extend into the return pipe 10, thus causing the water to flow therethrough into contact with the heat responsive element.

I reserve to myself a reasonable application 10 of the doctrine of equivalency commensurate with the state of the prior art and the terms of my appended claims.

Having thus described my invention, what I claim as new herein and desire to 15 secure by Letters Patent is:

1. In combination with the cooling system of an internal combustion engine embodying a radiator and a return pipe therefor, a heat-responsive element positioned in the 20 radiator and a tubular member co-operating with the return pipe orifice of the radiator and the heat-responsive element for directing the circulating medium against said heat-responsive element during the 25 return passage of said medium to said radiator.

2. A device for indicating the temperature of cooling water of an internal combustion engine, comprising in combination 30 a radiator, and a return pipe therefor, said radiator having a filler opening, a tubular member inserted in the return pipe of the radiator and projecting within the radiator below the filler opening thereof, and a 35 temperature-responsive indicating device mounted in and carried by the filler cap of said radiator, said indicating device projecting within the tubular member so as to contact at all times with the circulating 40 cooling medium therein.

3. In combination with a liquid circulating cooling system of an internal combustion engine, a radiator and a return pipe therefor, said radiator having a filler opening, 45 a heat-responsive indicating device mounted in and carried by the filler cap thereof, said indicating device projecting within the radiator below the filler opening, and a pipe projecting from the return pipe of the radiator and into the radiator below the filler opening, said pipe having an aperture 50 through which the indicating device projects, the end of said pipe being closed in order to cause the cooling medium to contact with the indicating device and pass 55 through said opening during its circulation through the system.

4. A device for indicating the temperature of cooling water of an internal combustion engine, comprising in combination 60 with the radiator and a return pipe therefor, said radiator having a filler opening, a tubular member inserted in the return pipe of the radiator, said tubular member being 65 substantially the diameter of the return

passage so as to receive substantially the entire flow of circulating cooling medium, said tubular member projecting within the radiator and below the filler opening thereof, and a temperature-responsive indicating 70 device mounted in and carried by the filler cap of said radiator, said indicating device projecting within the tubular member so as to contact at all times with the circulating cooling medium. 75

5. In combination with a cooling system of an internal combustion engine embodying a radiator and a return pipe therefor, said radiator having a filler opening, a temperature-indicating device mounted in and carried by the filler cap of said radiator and having a temperature-responsive part projecting within the radiator, a member provided with an unobstructed passage co-operating with the return pipe of the radiator 80 and the temperature-responsive part of the indicating device whereby the entire flow of the cooling medium will be caused to pass through said unobstructed passage and when circulating at all times to influence the 85 temperature-responsive part of the indicating device. 90

6. In combination with a cooling system of an internal combustion engine, a radiator and a return pipe therefor, said radiator 95 having a filler opening, an indicating device mounted in and carried by the filler cap thereof, said indicating device having a temperature-responsive part projecting within the radiator below the filler opening thereof, 100 a member provided with an unobstructed passage located in the return pipe of the radiator and substantially filling the same, said member projecting within the radiator and beneath the filler opening thereof, and 105 being formed to accommodate the heat-responsive part of the indicating device so that the cooling medium will be caused to contact therewith while circulating. 110

7. In combination with the cooling system of an internal combustion engine, including a radiator and means for returning the hot water from the engine into the upper part of the radiator, of a thermometer having a part supported in the upper 115 part of the radiator in such position as to be located in the stream of water entering the radiator.

8. In combination with the cooling system of an internal combustion engine including a radiator and a return pipe for the hot water from the engine, of means fed by the return pipe for maintaining a body of water at substantially the temperature of the water leaving the engine and at a substantially constant level at or above the level of the water in the radiator, and a temperature indicating instrument arranged to indicate the temperature of said body of hot 125 water. 130

9. In combination with the cooling system of an internal combustion engine including a radiator and a return pipe for the hot water from the engine, of means forming a chamber in the upper part of the radiator and connected with said return pipe and into which water from said return pipe discharges, and a temperature indicating instrument arranged to indicate the temperature of the water in said chamber.
10. In combination with the cooling system of an internal combustion engine including a radiator and a return pipe for the hot water from the engine, of means forming a chamber in the upper part of the radiator into which water from said return pipe discharges, said chamber being open at the top to permit said water to overflow, and a temperature indicating instrument projecting into said chamber.
11. The combination with the cooling system of an internal combustion engine including a radiator and a return pipe for the hot water from the engine, of a temperature indicating instrument including a temperature responsive element located in the radiator, and an open and unobstructed tube for conveying water from said return pipe into contact with said temperature responsive element.
12. The combination with the cooling system of an internal combustion engine in-
- cluding a radiator and a return pipe for the hot water from the engine, of temperature indicating means, including a temperature responsive element located in the radiator, and means for conveying water from said return pipe into contact with said element, the freedom of discharge of water into the radiator being substantially undiminished by said means.
13. The combination with the cooling system of an internal combustion engine including a radiator and a return pipe for the hot water from the engine, of means forming a chamber in the upper part of the radiator through which all of the water from said return pipe discharges into the radiator, and temperature indicating means having its heat responsive element in said chamber.
14. The combination with the cooling system of an internal combustion engine including a radiator and return pipe for the hot water from the engine, of temperature indicating means including a temperature responsive element, and means fitting within the return pipe and supported by engagement with the walls of the return pipe for directing water from said return pipe into contact with said temperature responsive element.

WILLIAM P. HAMMOND.
